UNITED STATES PATENT OFFICE.

ERNEST S. CORY, OF BIRMINGHAM, ALABAMA.

TOOL.

Application filed May 2, 1925. Serial No. 27,538.

To all whom it may concern:

Be it known that I, ERNEST S. CORY, a citizen of the United States, and resident of Birmingham, in the county of Jefferson and State of Alabama, have invented certain new and useful Improvements in Tools, of which the following is a specification.

My present invention relates to a device for laying off window jambs of either the plain or plowed type.

The principal object of the invention is to facilitate the laying off of the beveled bottom end of a window jamb which adjoins the sub-sill, and at the same time to provide means which will quickly indicate the points on the jamb adjacent the header for the bit holes which are afterward chiseled out to receive a single or pair of pulleys, as the case may be.

Another important object of the invention is the provision of a single device which will, in a few operations, do the work of several tools now found necessary, and in an efficient manner.

Further objects and advantages will appear as the description proceeds.

In order to accomplish the above end I have designed a device, and my invention includes a tool similar to a carpenter's square, except that the base of the L instead of having a single straight edge, has two edges in angular relation to each other equal to the angle which the upper surface of a sub-sill makes with the window jamb. The main branch of the L is provided with projecting points which are secured therein and project from the bottom of the tool so that when a blow is struck above the points, these points will be driven into the wood of the jamb and indicate therein the positions in which holes are to be bored by the ordinary bit, later to be chiseled out to receive the single or a pair of pulleys, commonly used. I contemplate making these projecting points removable and providing several series of holes in the tool so that the points may be removed from one hole to another in order to adapt the tool to various sized pulleys. Overlying all of the points I provide a leather, fabric or other protecting element which is secured to the tool so that the carpenter or mechanic using the tool may use his hammer or mallet and strike the leather or fabric, which will reduce objectionable sound to a minimum. In the use of the tool for plowed jambs in which there is a longi-

tudinal recess which is afterward adapted to receive the parting stop between window sash, I provide the tool with two alignment stops projecting from beneath the tool, which are adapted to lie in the longitudinal recess of this form of jamb in order to accurately position the tool, when using it as a template.

The invention further consists in the details of construction, arrangement, and combination of parts hereinafter shown and described.

I have illustrated in the accompanying drawings the most satisfactory form of which I am now aware, although obviously I do not wish to be limited to the form shown.

In this drawing:—

Figure 1 is a plan view of one form of my invention.

Fig. 2 is a sectional elevation along the line 2—2 of Fig. 1.

Fig. 3 is a sectional elevation along the line 3—3 of Fig. 1.

Fig. 4 is a plan view showing the device as used on the work.

Fig. 5 is a plan view showing the device as used in a plowed jamb.

Fig. 6 is a fragmentary plan view of a jamb showing the punch marks.

Referring now to the embodiment illustrated I have shown a square or tool consisting of the leg 1 and the leg 2. This tool may be made of any desired material such as wood or metal, although metal is preferable.

The inner edges of the legs 1 and 2 are straight and at right angles to each other and I propose to indicate on each edge beginning from the point of intersection of these edges, inches and fractions thereof. The outer edges of the leg 2 is arranged at an angle as indicated at 3 and 4, the angle of these edges being determined by the ordinary degree of angularity occurring between the upper surface of a sub-sill and the lower adjacent portion of a window jamb. The leg 1 of the tool is provided with screw threaded apertures 5 adapted to receive projecting points 6 screwed therein so that the tops of the points 6 are flush with the main surface of the leg 1. A plurality of these screw threaded apertures 5 are provided for a purpose which will be more fully described hereinafter.

Overlying the heads of the points 6 I provide a strike pad 7 of leather, fabric, or other desired material, and which is fastened to the leg 1 by means of screws 8.

5 The use of the tool is as follows:—

When it is desired to lay off a window jamb, two boards from which the jambs are to be cut are placed with their longitudinal edges adjacent and the tool placed thereon so that the inner edge of the leg 1 lies adjacent the outer true edge of one of the jambs. Inasmuch as these jambs are usually of a constant width, it is contemplated that a tool will be used so that the adjacent longitudinal edges of two jambs will pass through the point of intersection of the edges 3 and 4 of the leg 2. In such position, by drawing a pencil line along the edges 4 and 3, it will be apparent that two jambs may be marked at once making a proper angle to adapt it to engage the sub-sill of a window.

Having thus marked the angular end and measured off the proper length of the jamb, the juncture of the outer edges of the legs is then placed at a corner of the opposite squared end of the jamb so that the projecting points 6 occupy the position later to be taken by the pulleys. When the tool has been placed in such position, a blow of a hammer or mallet upon the strike pad 7 will drive the projecting points into the wood and thus indicate to the mechanic where the holes are to be drilled by the bit, instead of having to make several measurements with a rule to determine this position.

Obviously the projecting points 6 may be placed in any of the screw threaded apertures 5 to correspond with the various widths or lengths of pulleys used, and for this reason I provide a number of apertures 5 with which the projecting points 6 are interchangeable.

Some window jambs are known as plowed jambs, that is, they have a longitudinal groove therein usually of $\frac{1}{2}$ inch or thereabouts, into which is ordinarily inserted the

parting stop which separates the two window sash. In adapting the tool to the marking off or laying out of such jambs, I provide on the under side of the leg 1 alignment stops 9 secured to the leg 1 as by screws 10. These are preferably of metal and are so located with reference to the projecting points 6 that when the tool is placed on a plowed jamb the stops 9 in entering the groove on a plowed jamb, will accurately center the points 6. This saves the trouble of aligning the straight edge of the leg 1 with the straight edge of the jamb.

An aperture 11 is provided in the lower part of the leg 1 so that the tool may be hung up if desired.

Obviously the strike pad may be perforated to allow the projecting points to be removed therefrom and placed in other screw threaded apertures without removing the strike pad itself.

Having thus described my invention, what I claim is:—

1. A tool comprising a main leg and a supplemental leg, the inner straight edge on one leg joining an inner straight edge on the other at right angles, points secured to one leg and projecting from the surface thereof, and a strike pad secured to one of the legs overlying the heads of the projecting points.

2. A tool comprising a main leg and a supplemental leg, an inner straight edge on one leg joining an inner straight edge on the other leg at right angles, the supplemental leg having an outer edge making a predetermined angle with its inner edge, a gauge secured to the main leg comprising points projecting from the under surface thereof, a strike pad secured to the opposite side of the main leg and overlying the heads of the projecting points, and alignment stops secured to the under surface of the main leg.

In testimony whereof, I affix my signature.

ERNEST S. CORY.
